END LINER FOR GRINDING MILLS

Starks L. Miller, Denver, Colo., assignor to American Ball-Mill Company, Denver, Colo.

Application September 9, 1935, Serial No. 39,762

3 Claims. (Cl. 83—9)

This invention relates to improvements in grinding mills of the type employed in grinding ores and the like, which employ attrition bodies such as balls or rods. The invention relates more particularly to the construction of the end liners and the means for securing them in place.

The principal object of this invention is to provide sectional end liners, throat rings and ball-retainers that are individually removable without disturbing the other sections.

Another object is to provide a simple means for holding the sections in place and which can be readily released for the purpose of permitting the removal of the sections.

15 A further object is to provide means for securing sectional end liners, ball-retainers and throat rings in place in a grinding mill by the employment of radially acting forces.

The above and other objects that may appear as the description proceeds are obtained by means of a construction and an arrangement of parts that will now be described in detail and for this purpose reference will be had to the accompanying drawings in which the invention has been 25 illustrated, and in which

Figure 1 is a view, partly in section and partly in side elevation, showing a grinding mill constructed in accordance with this invention;

Figure 2 is a section taken on line 2—2, Figure 1, looking toward the discharge end of the mill;

Figure 3 is a section taken on line 3—3, Figure 1, looking toward the intake trunnion or the feed end of the mill;

Figure 4 is a view, partly in section and partly in elevation, looking in the direction of arrow 4, Figure 5;

Figure 5 is a section taken on line 5—5, Figure 4;

Figure 6 is a section taken on line 6—6, Figure 4;

Figure 7 is a section taken on line 7—7, Figure 5;

Figure 8 is a section taken on line 8—8, Figure 9;

Figure 9 is a section taken on line 9—9, Figure 8;

Figure 10 is a section taken on line 10—10, Figure 9;

Figure 11 is a section, taken on line 11—11, Figure 12;

Figure 12 is a section, taken on line 12—12, Figure 11;

Figure 13 is a section taken on line 13—13, Figure 11.

55 In the drawings reference numeral 5 designates the shell, numerals 6 and 7 the heads at the intake and the discharge end respectively, and numerals 8 and 9 designate respectively the intake and the discharge trunnions. The trunnions are mounted for rotation in bearings 10 carried on suitable supports 11. Located within the shell are a number of channelled girders 12, arranged in spaced parallel relation with the web toward the inside and the edges of the flanges in contact with the shell. Liner sections 13 are supported on the girders and held in assembled and spaced relation by means of curved wedges 14.

Since the invention here relates more particularly to the construction of and the method of securing the end liners, throat ring and discharge 15 grate in place the construction of the side liners will not be further described.

Referring now more particularly to Figures 1, 2 and 3, it will be seen that abutments 15 are secured to the inner surfaces of the heads. The 20 abutments may be rings, which are secured in place by welding or by bolts or rivets, or they may be formed from a number of separate sections secured in place by similar means.

It will be observed that the inside edges of the 25 abutments are beveled so as to provide an undercut surface, as shown most clearly in Figure 9.

At the inner end of the intake or feed trunnion 8 a sectional throat ring is provided, which consists of a plurality of sections 16. In the example 30 illustrated the throat ring is formed from four sectors each of 90° angular extent. The outer surface of each sector 16 is provided with an outwardly facing beveled shoulder which is so positioned that it will engage the inside of the abutments in the manner shown most clearly in Figure 9.

The radial surfaces of the sectors 16 are provided with curved tapering grooves for the reception of curved wedges 18 whose wider ends are 40 toward the inside as shown most clearly in Figure 8. The sectors 16 are of such size that they can be put into position and then moved radially until the shoulders 17 engage the cooperating beveled shoulders of the abutments. After the 45 blocks or sectors 16 are properly positioned, the wedges 18 are inserted and driven home until the pressure of the shoulders 17 against the abutments is sufficient to hold the sectors in place.

At the inner end of the discharge trunnion 9 a sectional ball-retainer is positioned and held in place by means substantially identical with that employed with the throat ring. The ball-retainer has been shown as comprising four sector-shaped parts 19 of a transverse section like 55

that illustrated in Figure 5. Each part 19 has an outwardly directed shoulder 17 while adjacent radial sides have curved tapered grooves for the reception of the wedges 18.

5 From Figures 1, 2 and 3 it will be seen that the inside of the discharge head 7 is provided with a plurality of truncated triangle-shaped liner sections 24, whose shape and the manner of securing them in place is most clearly shown in Figures 4 10 and 5. It will be seen from Figure 4 that the end liner sections are so positioned that the sides lie in radii bisecting the girders 12 and that their bases are therefore formed from two short straight sections *b* and *c*.

15 An elongated wedge 25 is secured transversely of each girder and serves as an abutment for the straight end walls *b* and *c* of adjacent sections 24. The opposing sides of adjacent sections are provided with tapering arcuate grooves for the 20 reception of the curved tapering wedges 18.

In order to enhance the holding function of keys 18 throughout the maximum period of wear on the liner sections 24, the heads 6 and 7 are provided with pockets 30 as illustrated in Figures 25 5, 7, 9 and 10. The liner sections 24, 24a and 24b have flanges 31, 31a and 31b respectively which extend into the pockets 30 when the keys 18 are driven into the grooves.

It will be noted in Figure 5 that the keys 18 30 extend through the grooves to a greater depth than the normal thickness of the liner sections 24, indicated by the dotted line.

From the foregoing, it will be apparent that no matter how thin the end liners wear, there 35 will be enough of the key 18 in the grooves within the flanges 31 to prevent the sections from separating.

When the sections are positioned as shown in Figure 4, and separated by the wedges, the end 40 walls *b* and *c* will be forced radially against the wedges 25 and the end liners will thus be securely held in place without the use of bolts; the wedge 25 having its inner edges so beveled as to undercut the adjacent liner. When an end liner section 45 is to be removed a wedge at one side is driven out after which the wedge on the opposite side can readily be removed, thereby completely releasing the section.

The liners on the inside of head 6 are somewhat 50 differently formed and are held in place by specifically different means, all as will now be described.

The liners of head 6 are each formed from two parts 24a and 24b, which together equal one liner 55 24. The abutment or abutments 15a have both the inner and outer edges beveled, in the manner shown in Figure 9, and the girders have wedges 25 secured thereto the same as in Figure 4. The bottom side of section 24a and the top of section 60 24b are provided with cooperating curved tapering grooves for the reception of a curved wedge 18 which serves to force the inner end of section 24a against the outer edge of the abutments 15a and the outer end of section 24b against the 65 wedge 25.

In Figures 11, 12 and 13 another way of securing the liners in position has been shown. The abutment 15a has been illustrated as a ring having both its inner and its outer edges beveled. 70 This ring is secured to the head in any suitable way and instead of being a continuous ring as shown, may be formed from a plurality of segments.

Instead of the wedges 25 shown in Figure 9 a 75 curved or segmental shaped lug 26 is attached

to each girder near its end, the base of each liner section 24d is provided with a curved tapering groove for the reception of a correspondingly curved tapered wedge 18b which is positioned between the lug 26 and the inside of the head. 5 The wedge 18b is somewhat conical, and the groove in section 24d is similarly inclined with the result that when the wedge is driven home the resultant force will be along line *a*—*b* and tends to force the sections against the inside of 10 the head.

It will be seen from the above description that the parts are held in place by a radial force which acts to expand the throat ring, the grate and the end liners, radially against abutments having beveled edges, which abutments have been indicated by numeral 15.

The curved wedges employed for holding the end liners in place have been designated throughout the several views by numeral 18 as they are all 20 alike except as to size.

Throughout the claims the words "liners" and "liner sections" will be employed in a sense broad enough to include the throat ring and grate sections as well as the other liner sections, as the 25 several kinds of liners are all secured in place in the same way.

Attention has previously been called to the fact that the abutments may be rings or a plurality of separate sections arranged in the form of a 30 circle and therefore whenever the expression "angular abutment" or "ring abutment" is used, it is to be understood as including the equivalent thereof.

Having described the invention, what is claimed 35 as new is:

1. In a grinding mill, a shell, a head at an end thereof, an abutment on the head, the abutment having an undercut shoulder, a girder on the shell, a lug on the girder spaced from an end 40 thereof, a liner positioned between the girder and the abutment, the liner having a beveled shoulder for engaging the undercut shoulder on the abutment, there being a groove in the liner, and a spreader positioned in the groove and engaging 45 the girder between the lug and the head for producing a force urging the shoulders into engagement.

2. A grinding mill having a shell, a head at an end thereof, the head having a trunnion, liners 50 for the head, comprising a central portion formed from several parts, each part having a portion extending into the trunnion and another portion projecting over the surface of the head immediately surrounding the trunnion, an abutment 55 on the head adjacent the trunnion, having its inner edge undercut, the liners having outwardly facing shoulders inclined to fit the shoulder on the abutment, means for expanding the liner assembly 60 immediately surrounding the trunnion, an abutment on the head adjacent the trunnion, having its inner edge undercut, the liners having outwardly facing shoulders inclined to fit the shoulder on the abutment, a second abutment means positioned adjacent the periphery of the head, the inner edge of the outer abutment means being undercut, a plurality of liners positioned between the two 65 abutments and provided with outwardly directed shoulders shaped to engage the undercut shoulder on the last-mentioned abutment, and means for expanding the liner assembly to secure interlocking engagement between the shoulders. 70

3. A grinding mill having a substantially cylindrical shell, a head for closing one end thereof, the head having a tubular trunnion, liners for the inside of the head, the liner comprising a central portion formed from several sector-shaped 75

parts, each part having a portion extending into the trunnion and another portion projecting over the surface of the head immediately surrounding the trunnion, an annular abutment attached to 5 the inner surface of the head in concentric arrangement with the trunnion, the abutment having both its inner and its outer edges beveled and undercut, the liners having outwardly facing shoulders inclined to fit the shoulder on the inside 10 of the abutment, means for expanding the liners to increase its diameter and force the shoulders thereof into interlocking engagement with the inner shoulder on the abutment, a second abutment means positioned adjacent the periphery of the head and spaced from the first abutment, the inner edge of the outer abutment means being beveled and undercut, a plurality of two-part, truncated, sector-shaped liners located in the annular area between the abutments, each part 5 of the liners having a shoulder facing the undercut shoulder of the adjacent abutment and wedge means interposed between the two parts of each liner for expanding the annular liner assembly radially to secure engagement between the shoulders of the abutment and the shoulders of the liners.

STARKS L. MILLER.
